UNITED STATES PATENT OFFICE

WILLIAM J. MUNDT, OF PIERRE, SOUTH DAKOTA

PUMP-OPERATING MECHANISM

Application filed June 14, 1928. Serial No. 285,473.

The object of this invention is to provide a simple, inexpensive and efficient device whereby the work of operating a lift pump will be lessened and the stroke of the pump rendered even. In lift pumps, especially in deep wells, the strokes of the operating mechanism are unequal inasmuch as on the upstroke of the pump rod, the weight of the rod and the parts mounted thereon as well as the weight of the water must be lifted, whereas on the downstroke of the pump there is no weight of water to be lifted and the weight of the pump and the attached parts aids in making the stroke. In hand-operated pumps, the operation is consequently very laborious, while in power-operated pumps the supply of power makes the expense out of proportion to the results, especially in localities where the water supply is uncertain and is located at a great depth. My invention provides simple means whereby the upstroke of the pump will be mechanically aided without imposing strain upon the operator so that the up and down strokes of the pump rod will be substantially even. The invention is illustrated in the accompanying drawing and will be hereinafter fully set forth.

In the drawing:

Figure 1 is an elevation of a pump having my improved equalizing mechanism connected therewith;

Fig. 2 is a horizontal section on the line 2—2 of Fig. 1;

Fig. 3 is an enlarged detail perspective view of one form of spring hanger;

Fig. 4 is a similar view showing another form of spring hanger, and

Figs. 5 and 6 are detail views showing different forms of pump rod clamps.

The pump illustrated at 1 may be of any approved detail construction and includes a pump rod 3 operated by a hand lever 4, the pump being mounted upon a well curb or platform 2 in the usual manner. In carrying out my invention, there is provided a standard 5 which is mounted upon the platform at the side of the pump remote from the handle 4, and this standard may be of wood or metal but is preferably constructed of two metal channel bars having their channels disposed

outwardly, as will be understood upon reference to Fig. 2. The lower end of the standard is connected with the platform by a hinge 6 at the side remote from the pump so that when repair of the pump is necessary the standard and the parts mounted thereon may be swung away from the pump to afford access to all sides of the same. This hinge construction also permits a rocking movement of the standard whereby to accommodate the angular movement of the equalizing lever relative to the pump rod. The equalizing lever 7 extends between the members of the standard and is pivoted thereto adjacent the upper end of the same, the standard being provided with a plurality of openings 8 to accommodate the pivot bolt 9 and permit the lever to be set at the proper height to accommodate any desired pump rod. The shorter arm of the equalizing lever extends toward the pump rod and has pivoted to its extremity clamping plates 10 which extend at opposite sides of the pump rod 3 and are firmly attached thereto by clamping bolts, indicated at 11, inserted through the ends of the clamping plates adjacent the opposite sides of the pump rod. The longer arm of the equalizing lever extends away from the standard and is provided adjacent its end with a plurality of openings 12 through any one of which may be inserted a bolt 13 to attach a spring hanger 14 thereto. This spring hanger, as shown most clearly in Fig. 3, consists of a plate or web 15 having a foot 16 at its lower end extending laterally therefrom and terminating in a plurality of upturned lugs or hooks 17 over which may be engaged eyes at the upper ends of tension springs 18. The lower ends of the springs are engaged in like manner with a lower spring hanger 19 which is similar in form to the upper spring hanger but is somewhat longer and provided with a plurality of openings 20 to accommodate the attaching bolt and provide for adjusting the tension of the springs. Any number of springs may be employed and they may be of any size or strength according to the size of the pump and other working conditions, and it will be understood that by engaging the pivot bolt 13 in a selected opening 12, the force exerted

by the equalizing lever may be varied to suit conditions and this adjustment will also serve to regulate the tension of the springs. The lower hanger is secured to the outer end of a 5 supporting arm 21 which has its inner end firmly secured between the members of the standard 5 and a brace 22 has its upper end attached to the outer end of the arm 21 by the same bolt which secures the lower hanger 10 19 thereto, the lower end of the brace being passed between the members of the standard and adjustably secured therein by a bolt 23 inserted through one of a series of openings 24 in the lower end of the brace.

15 When the pump rod 3 is forced downward, the attached end of the equalizing lever 7 will, of course, swing downwardly and the outer end of said lever will swing upwardly thereby expanding the springs 18 and increasing the 20 tension of the same. When the ensuing up-stroke is imparted to the pump rod, the springs 18 will, of course, contract and will relieve the operator of the lifting strain, the spring being adjusted to counter-balance or 25 overcome the weight of the load normally raised by the pump. By properly adjusting the brace 22 and the spring hangers, the force of the equalizing lever may be nicely regulated according to the normal load upon the 30 pump and to acquire the desired tension in the springs. The springs tend constantly to assume their contracted condition and, of course, will commence to contract immediately upon the completion of the down-stroke of 35 the pump so that the work of operating the pump will be minimized and the strokes of the pump be uniform.

It may sometimes be more convenient or 40 desirable to employ springs having hooks instead of eyes at their ends and in such event the spring hanger 25 shown in Fig. 4 may be employed. This hanger is of the same form as the hanger shown in Fig. 3, except that the lugs or hooks 17 are omitted and openings 26 45 are formed through the lateral web of the hanger to be engaged by the hooks at the ends of the springs.

The clamping plates by which the equalizing lever is connected to the pump rod may 50 be of various forms as may be most desirable under any given circumstances so that the equalizing mechanism may be disposed in the most advantageous angular relation to the pump. The clamping plates shown in Fig. 1 55 are straight flat plates which will be used when the equalizing mechanism is disposed in the plane of the pump rod and the pump handle. If, for any reason, it becomes necessary to dispose the equalizing mechanism at 60 an angle to the pump rod and the pump handle, clamping plates, such as shown in Fig. 5, 65 may be used. These clamping plates 27 are similar to the clamping plates 10 but have their end portions disposed in angular relation. It may sometimes be desirable to em-

ploy clamping blocks 28, as shown in Fig. 6. These blocks are provided with recesses 29 in the edge or side presented to the pump rod so that the pump rod may be received therein. It will be understood that whatever form 70 of clamping plate or block is employed they are used in pairs disposed at opposite sides of the pump rod and firmly secured by bolts inserted through openings provided in their ends.

Having thus described the invention, I 75 claim:

1. A pump equalizer comprising a standard, an equalizing lever pivoted directly to the upper portion of the standard, a clamp to be secured to a pump rod and to which one end of the lever is pivoted, an arm secured to and projecting from the standard below the equalizing lever, and tension springs connected with and extending between said arm and the end of the equalizing lever remote 80 from the pump rod.

2. A pump equalizer comprising a standard, an equalizing lever pivoted directly to the upper portion of the standard, a clamp pivoted to one end of said lever and secured around a pump rod, an arm secured to the standard and projecting therefrom below the lever, hangers carried by the ends of the lever and said arm respectively, and tension springs 90 engaged with and extending between said hangers.

3. A pump equalizer comprising a standard, an equalizing lever pivoted directly to the upper portion of the standard and adjustable vertically thereon, means for attaching one end of the lever to a pump rod, a hanger attached to the opposite end of the lever and adjustable longitudinally thereof, an arm secured to the standard and projecting therefrom below the lever, a hanger carried by the outer end of said arm and adjustable across the arm, the hangers having marginal hooks, and tension springs extending between the hangers and having their 100 ends engaged with the hooks thereon.

In testimony whereof I affix my signature.
